UNITED STATES PATENT OFFICE.

STEPHEN G. BALDWIN, OF MARION, INDIANA.

INK-WELL.

SPECIFICATION forming part of Letters Patent No. 404,246, dated May 28, 1889.

Application filed October 18, 1888. Serial No. 288,434. (No model.)

To all whom it may concern:

Be it known that I, STEPHEN G. BALDWIN, of Marion, in the county of Grant and State of Indiana, have invented certain new and useful Improvements in Ink-Well; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in inkstands, and has for its object to provide a device of this class that will be very simple, composed of but few parts, and one that will not only be cheap in first cost, but will be durable and tasty and neat in appearance.

With these ends in view my invention consists in certain novel features of construction and combinations of parts, more fully described hereinafter, and particularly pointed out in the claim.

Referring to the accompanying drawings, Figure 1 is a perspective view of the complete device; and Fig. 2 is a vertical section, the lower point of the mouth-piece being broken away.

Like letters of reference mark the same parts throughout the several views.

A represents a closed reservoir, made of glass or any other suitable material, provided with a threaded opening, B, through its top wall.

C indicates a vertically-adjustable mouth-piece, the lower end of which is smaller than the top and rounded off to fit a pocket, b, in the bottom of the reservoir, directly beneath the threaded opening through the top of the reservoir. Said lower end is also provided with a small aperture, a, through which the ink is forced when the mouth-piece is screwed down. It will be seen that the pocket b is located at the lowest point in the reservoir and immediately under the mouth-piece, so that when there is a drop of ink in the reservoir it can be forced up into the mouth-piece for use.

The hollow plug or mouth-piece is open at its top, and is externally screw-threaded, pref-

erably, throughout that portion of its length, which is of uniform diameter, to screw in the threaded opening of the closed reservoir. 55 The top edge of the mouth-piece is surrounded by a milled ring or rim, d, by which the mouth-piece can be readily turned to adjust the same. The mouth-piece is of such length that it can be adjusted so that its lower end 60 will extend into the recess of pocket b.

The operation of my improved device is as follows: Supposing the well to be in the position shown in Fig. 1, and it is desired to fill the reservoir with ink or any other liquid, 65 the operator in filling the receiver may either pour the ink slowly into the top of the mouth-piece and let it pass down through the aperture a into the receiver, or, a better way still, can withdraw the mouth-piece C entirely 70 from the casing, and then pour the liquid directly into the reservoir, and then the mouth-piece can be inserted. This is the preferred way of filling and is deemed the best.

When it is desired to use the ink and the 75 reservoir should happen to be but partly filled, it will only be necessary to screw the mouth-piece downward until the aperture a reaches the level of the ink, when the same will begin to enter said opening a and pass 80 up into the hollow mouth-piece. It will be readily seen that with my improved mouth-piece the ink will be forced into it when screwed down, no matter if there is but a very small quantity of ink in the reservoir, or 85 if it is full.

The aperture or opening in the lower part of the mouth-piece can be made just large enough to enable the user to insert the pen into it, and thereby run no risk of getting the 90 fingers soiled by inserting the pen too deep into the ink. This could be accomplished very easily by regulating the mouth-piece so as to allow only a small quantity of ink to enter it.

It will be readily seen that the article described will not only present a neat appearance, but a great deal of ink can be saved by its use, as there will be no danger of the same becoming muddy or evaporating.

It is evident that the invention is not limited to any particular size or shape.

What I claim is—

An inkstand consisting, essentially, of a

closed reservoir having a central threaded opening through its top wall, a pocket in the bottom of the reservoir beneath said opening, a hollow plug or mouth-piece located in said 5 opening in vertical adjustment, having its upper end open and surrounded by a milled rim and its lower end shaped to fit in said pocket and provided with an ink-inlet, the portion of the plug between the rim and said end being 10 of uniform diameter and externally threaded

throughout to screw vertically in said opening, substantially as described.

In testimony that I claim the foregoing as my own I affix my signature in presence of two witnesses.

STEPHEN G. BALDWIN.
